FISHING REEL

Morris E. Wood, Bronson, Mich., assignor to Higbie Manufacturing Company, Rochester, Mich., a corporation of Michigan

Filed Nov. 9, 1960, Ser. No. 62,789

Term of patent 14 years

(Cl. D31—4)

The lines appearing on the handle in FIGURE 2 represent surface ornamentation.

I claim:

The ornamental design for a fishing reel, as shown and described.
